UNITED STATES PATENT OFFICE.

MOPRIS SELLERS, OF CHICAGO, ILLINOIS.

TIE-PLATE.

No. 894,986.

Specification of Letters Patent.

Patented Aug. 4, 1908.

Application filed February 1, 1908. Serial No. 413,878.

To all whom it may concern:

Be it known that I, MORRIS SELLERS, a citizen of the United States, residing at Chicago, in the county of Cook and State of Illinois, have invented certain new and useful Improvements in Tie-Plates, of which the following is a specification.

My invention relates to railroad-rail tie-plates and has for its object to provide a tie-plate which shall have projecting ribs on its under surface so arranged and constructed as to give the plate an effective grip or anchorage on the tie with a minimum of injurious disturbance of the fibers of the wood at the surface of the tie and, at the same time, to prevent the rotting of the portion of the tie covered by the plate, by the exclusion therefrom of water.

The invention, in one of its preferred embodiments, is illustrated in the accompanying drawings, in which:

Figure 1 is a perspective view of a tie plate of my invention in position on the tie with the rail seated thereon. Fig. 2 is an inverted plan view of the tie plate; and Fig. 3 is a section on line 3—3 of Fig. 2, looking in the direction of the arrows, showing also portions of the rail and tie.

Like characters of reference indicate like parts in the several figures of the drawings.

4 represents a tie, 5 an ordinary T-rail, and 6 a tie plate provided with the upstanding rib 7, against which the rail flange abuts, and perforated at 8, 8, 8, for the usual spikes 9. Any other means may be employed for holding the rail flange, tie plate and tie together. It has been usual to provide the under side of tie plates of this character with sharp, cutting edges or ribbed projections which cut into the body of the tie and form an anchorage for the plate. Devices of such character obviously cut and disturb the fibers of the tie and thereby increase the susceptibility of the tie to rot. This is particularly objectionable with creosoted ties or with ties given a similar superficial treatment. The spike cuts through the treated portion of the wood at the surface and lets water through into the untreated part.

In the use of tie plates of this sort it has also been found that the part of the tie under the plate is much more apt to rot than the parts not so covered. This is because the water, which may run freely off and evaporate from the uncovered part of the tie, collects and stands under the tie plate, causing

the tie eventually to rot in these places. In order to obviate these several disadvantages, I provide the under surface of the tie plate with ribs which are more or less shallow and blunt, so that they crush and grip the fiber of the wood rather than cut into the same. In order to get a proper grip on the tie, a number of these ribs are provided. Preferably, the ribs, at the center of the plate at least 60 extend diagonally across the plate in intersecting lines, indicated by the numeral 10 in the drawings. The whole under surface of the plate may be provided with diagonal ribs of this sort, if desired. This construction, it 65 will be seen, divides the surface of the plate into a number of inclosed spaces 11 separated from each other by the ribs. By means of this arrangement of the ribs, water will not penetrate for any considerable distance under the plate and the plate will grip the fiber of the wood in all directions. I also prefer to construct the plate with a rib 12, which I term a box rib, and which runs entirely 70 around the under face of the plate near the edge. This rib aids in giving the plate a grip upon the tie and also serves to exclude moisture. Preferably this rib is made somewhat lower than the ribs at the center part of the plate, so that the greater pressure at the center 75 will not cause the breaking of the plate. Parallel ribs 13, 13 may also be provided. This arrangement of diagonal, intersecting ribs and a box rib gives the plate a firm grip 80 upon the tie, without cutting or penetrating the tie, and effectively excludes water.

In practice it has been found that where moisture enters between the tie and the tie plates, even though the water does not penetrate deeply in the tie, a softening of the fiber and disintegration of the tie rapidly ensues. Consequently while the box rib may assist by giving an additional grip of the tie plate upon the face of the tie, it is not essential for that purpose, but is of primary value because it 90 excludes moisture at all points.

A further important advantage of my invention arises from the fact of the extensive and increasing use of the railroad rails as means for conducting electric currents for 105 various purposes, such, for example, as in block signal systems. For such purposes the rail will be sufficiently insulated from the earth by the wooden ties when the tie is dry, but, as is well known, when moisture enters 110 between the tie and the rail, the electrical conductivity of the tie is greatly increased

and the aggregate loss of current or voltage resulting therefrom is very noticeable and exceedingly objectionable.

Where my improved tie plate is used, substantially all of that portion of the tie surface which contacts with the tie plate, which in turn makes contact with the rail, is kept dry at all times and that portion of the tie surface which contacts with the tie plate, but is not so protected, is so limited in area that it will readily dry out. The result is that for all practical purposes the tie plate at all times rests upon dry wood, which sufficiently insulates the rail to prevent objectionable loss of voltage in the signal currents sent over the rail.

The arrangement of diagonal ribs shown in the drawings is effective in excluding moisture from that part of the tie surface covered by that portion of the plate provided with diagonal ribs. In the preferred form, the plurality of intersecting ribs, whether of diagonal arrangement or otherwise, under that portion of the tie plate which directly carries the rail base, serves to give the tie plate the required grip upon the tie surface, while the marginal or box rib effectively excludes moisture.

Obviously with an article used in such vast numbers as tie plates, its utility largely depends upon its being of such a character that it may be rapidly and cheaply made from the most suitable materials. My improved tie plate has not only the service advantages described, arising from the character of the ribs upon its under face, but those ribs are of such a character and are susceptible of such an arrangement as to permit of producing these tie plates not only by rolling, but by a very simple rolling process eliminating most of the successive steps which are necessary in rolling tie plates with projecting spikes or ribs which are driven into the tie. Consequently by my invention I am enabled to produce a tie plate of wrought iron or steel having a maximum of utility and at a minimum of cost. These plates are preferably rolled in an ordinary rolling mill from wrought iron, which is the material best adapted for use in such an article and to resist erosion and corrosion.

While I have referred to the ribs on my tie plate as being "non-cutting", it should be understood that, while such ribs may superficially crush or break the fiber and possibly to a trifling extent cut it, the term "non-cutting" is used to distinguish these ribs from ribs which so penetrate the tie, in a manner similar to the penetration by a spike, as to constitute attaching members. The ribs on my tie plate do not constitute attaching members and, when the spikes are removed, the plates may be lifted from the tie,

but with the rail and spikes in place, such ribs grip the tie so as to prevent lateral displacement of the tie plate. They embed themselves in the surface of the tie by crushing into the fiber sufficiently for this purpose.

I wish it to be understood that I do not desire to limit myself to the exact constructions and arrangements shown in the drawings, as some modifications might be made without departure from my invention.

I claim:

1. A railway tie plate, the under surface of which is provided with a box rib extending all around such surface near the edge thereof, substantially as and for the purpose described.

2. A railway tie plate, the under surface of which is provided with a box rib extending all around such surface near the edge thereof, and a plurality of intersecting ribs within such box rib, substantially as and for the purpose described.

3. A railway tie plate, the under surface of which is provided with a box rib extending all around such surface near the edge thereof, and a plurality of intersecting ribs in the center of the plate within such box rib, the vertical dimension of the box rib being less than that of the central ribs, substantially as and for the purpose described.

4. A railway tie plate, the under surface of which is provided with a plurality of ribs dividing all of such surface into a plurality of completely inclosed spaces, substantially as and for the purpose described.

5. A railway tie plate, the under surface of which is provided with a box rib extending all the way around such surface and near the edge thereof, and a plurality of intersecting ribs running diagonally across such surface and dividing the same into a series of inclosed spaces, substantially as and for the purpose described.

6. A railway tie plate, provided on its under side with a plurality of non-cutting ribs adapted to be embedded in the surface of the tie and arranged to substantially exclude moisture from entering between the tie and the tie plate.

7. A tie plate, provided on its under surface with a plurality of non-cutting ribs adapted to be embedded in the tie directly under the rail, so as to prevent lateral displacement of the tie plate, said tie plate being provided on its under surface with other non-cutting, marginal ribs extending all around such surface, whereby moisture is substantially excluded from admission between the tie plate and the tie.

MORRIS SELLERS.
